UNITED STATES PATENT OFFICE.

THOMAS J. DOWD, OF NEW YORK, N. Y.

MOLD AND CORE PIN THEREFOR.

Application filed January 19, 1926. Serial No. 32,326.

This invention relates to molds, and has for one of its objects the provision of a novel and simple device of this character which shall be especially adapted for use in the manufacture of a combined rubber heel and arch support for shoes.

With the foregoing and other objects in view, the invention consists of the novel construction, combination and arrangement 10 of parts hereinafter fully described and claimed, and illustrated in the accompanying drawings, wherein:

Figure 1 is a perspective view of a mold constructed in accordance with my invention, 15 Figure 2 is a top plan view of the bottom plate or section of the mold,

Figure 3 is a bottom plan view of the top plate or section of the mold,

Figure 4 is a perspective view of the bottom plate or section of the mold,

Figure 5 is a detail view in side elevation of one of the pins of the mold,

Figure 6 is a top plan view of one of the mold pins,

25 Figure 7 is a bottom plan view of one of the mold pins,

Figure 8 is a bottom plan view of the combined rubber heel and arch support adapted to be made by the mold,

30 Figure 9 is a view in side elevation of the combined rubber heel and arch support,

Figure 10 is a sectional view taken on the plane indicated by the line 10—10 of Figure 8, and

35 Figure 11 is a sectional view taken on the plane indicated by the line 11—11 of Figure 9.

Corresponding and like parts are referred to in the following description, and designated in the several views of the accompanying drawings, by similar reference characters.

The article adapted to be made by the mold forming the subject-matter of this 45 application, comprises, as shown in Figures 8-11, a heel 1 and a support and cushion 2 which are to be made of rubber and nailed to the heel and arch of a shoe respectively. The support and cushion 2 extends forwardly and upwardly from the heel 1, but rests flat on the ground when in use so that the arch of the foot will be supported from the ground up. The slight upward and forward inclination of the support and cushion

50 2, allows for the compression of this part under the weight of the body thereon, and

these parts are provided in their upper sides with recesses 3 and 4, respectively. The lateral sides 5 and 6 of the support and cushion 2 extend downwardly and inwardly. 60 The heel 1 and support and cushion 2 are provided with openings 7 for the reception of the nails employed to secure them in place. Apertured disks 8 embedded in the heel 1 and support and cushion 2 with their openings registering with the openings 7, are adapted to prevent the nails from being driven all the way through the heel and support and cushion. The heel 1 and support and cushion 2 are provided in their 70 under sides with suction recesses 9 which surround the outer ends of the openings 7 and are of substantially elliptical formation. The recesses 9 are arranged with their major axes extending transversely of the 75 heel 1 and support and cushion 2, and their lateral or forward and rearward sides incline upwardly and inwardly as shown at 10.

The mold comprises a bottom plate or section 11 and a top plate or section 12. The 80 bottom plate 11 is provided with a recess 13 opening out through the top side thereof and having side and bottom walls similar in contour to the corresponding parts of the heel 1 and support and cushion 2. That 85 part of the bottom plate 11 that is located forwardly beyond the recess 13 is of reduced thickness as shown at 14. This plate is provided at opposite sides of the recess and adjacent the forward end thereof with 90 standing lugs 15, the top sides 16 of which are of arcuate formation and the rear sides 17 of which are perpendicular to the top side of the plate. The inner sides of the lugs 15 constitute continuations of the side 95 walls of the recess 13.

The top plate 12 is provided in its bottom side with recesses 18 for the reception of the lugs 15, and that part thereof that is located forwardly beyond the recesses 18 is 100 of increased thickness, whereby to adapt this plate to lie in full abutting contact with the bottom plate 11. The bottom side of the top plate 12 is also provided with core members 19 and 20 which in contour are similar 105 respectively to the recesses 3 and 4 of the combined heel and arch support.

When the plates 11 and 12 are secured together there will be provided a closed chamber having a lateral wall similar in 110 contour to that of the lateral side of the combined heel and arch support, a bottom

wall similar in contour to the bottom side of the article and a top wall similar in contour to the top side of the article. The reduction of the thickness of the bottom plate 11 forwardly beyond the recess 13, permits the finished article to be readily removed from the recess when the plates 11 and 12 are separated. The bottom plate 11 is provided at its corners with upstanding pins 11^a and the top plate 12 is provided in its corners with openings 12^a for the reception of the pins, whereby to permit the plates to be readily assembled with the core members 19 and 20 in proper position with respect to the recess 13 and prevent the plates from having any relative movement during the process of vulcanization.

The bottom wall of the recess 13 is provided with openings 21 for the reception of the shanks 22 of pins 23 which are adapted to form the openings 7 and recesses 9 in the heel and arch support and which are adapted to support the washers 8 during the vulcanization process. The pins 23 are provided above the shanks 22 with enlarged portions 24 which rest on the bottom wall of the recess 13 to support the pins in place and which in contour are similar to the recesses 9. The pin portions 24 form the recesses 9; and above these portions the pins are provided with stems 25 the upper portions of which are of reduced diameter to provide shoulders 26 which constitute rests for the washers 8.

In practice, the pins 23 are first placed in the openings 21, and thereafter the washers 8 are placed on the pins in a manner to be supported by the shoulders 26 thereof. The rubber is then placed in the recess 13, and after this has been done the top plate 12 is applied to the bottom plate 11 and secured in full abutting contact

therewith by a press. After the vulcanization process, and the removal of the mold from the press the top plate 12 is removed 45 from the bottom plate 11, and after this has been done the completed article may be readily withdrawn from the bottom plate 11.

It should be understood that the drawings are merely illustrative and do not pretend to give exact proportions. Furthermore, the said drawings are illustrative of a preferred construction, it being my expectation that various changes and modifications 55 may be made without departing from the spirit and scope of my invention.

What is claimed is:

1. A mold of the character set forth, comprising a bottom plate provided with a 60 recess, lugs extending upwardly from opposite sides of the recess, and a top plate having core portions and recesses for the reception of the lugs.

2. A mold of the character set forth, comprising a bottom plate having a recess, lugs extending upwardly from the bottom plate at opposite sides of the recess and having curved top sides and perpendicular rear sides, and a top plate having core portions and recesses similar to the contour 70 of the lugs.

3. A mold of the character set forth, comprising a bottom plate provided with a recess and lugs extending upwardly from opposite sides of the recess, dowel pins extending upwardly from the plate, and a top plate having core portions and provided with recesses for the reception of the lugs 80 and openings for the reception of the pins.

In testimony whereof I affix my signature.

THOMAS J. DOWD.
